UNITED STATES PATENT OFFICE.

EDWARD W. ANGER, OF CHICAGO, ILLINOIS.

WEAR-PLATE FOR TRUCK JOURNAL-BOXES.

1,325,772.

Specification of Letters Patent. Patented Dec. 23, 1919.

Application filed January 2, 1919. Serial No. 269,306.

To all whom it may concern:

Be it known that I, EDWARD W. ANGER, a citizen of the United States, residing at Chicago, in the county of Cook and State 5 of Illinois, have invented new and useful Improvements in Wear-Plates for Truck Journal-Boxes, of which the following is a full, clear, concise, and exact description, reference being had to the accompanying 10 drawing, forming a part of this specification.

This invention relates to an improved form of wear-plates for truck journal-boxes, and more particularly to an improved form 15 of chafing or wear-plate of this type which may be easily and rapidly installed without the use of tools but which, nevertheless, is solidly and rigidly held in position, whereby rattling between the wear-plates and 20 joining apparatus is substantially avoided.

One of the objects of this invention resides in the production of an improved form 25 of wear-plate which will eliminate the various objections and disadvantages which are now common to commercial forms of wear-plates, such as the trouble and difficulty usually attending the installation and removal of these plates in position on the journal-boxes, frequently resulting in the 30 destruction of said boxes, rattling due to the wear-plate because the same is not positively and rigidly held in position, and other disadvantages which will become apparent from the following detailed description.

35 A further object of the invention resides in the production of an improved wear-plate which may be cheaply manufactured but which, at the same time, in the practical and commercial use thereof, gives very effective, 40 economical, and practical results.

Other advantages of this invention will become apparent from the following detailed description, the accompanying illustration, and the appended claims.

45 Heretofore it has been common commercial practice to locate wear-plates on journal-boxes in position either by electric welding or riveting or analogous schemes, with all of which special tools are required both 50 to install and remove the plates, and with all of which the installation and removal of the plates is a prolonged and rather expensive operation, and one which could only be effectively accomplished in a shop equipped 55 with elaborate tools and paraphernalia effective for performing this operation. Also

when the gib or wear-plates are permanently secured to the journal-box by means of rivets, bolts, welding, etc., the removal of said plates frequently results, due to the 60 permanent connection, in the destruction and complete loss of the box. With wear-plates constructed in accordance with this invention, no special tools of any kind are required for either installing or removing 65 the wear-plates, and, consequently, plates of this type may be either installed or removed anywhere, along the right of way, the work of installing and removing usually being 70 performed at division shops. Also the use of gib plates of this type very materially prolongs the life of journal-boxes.

The preferred form of this invention is illustrated in the accompanying drawings, in which—

75 Figure 1 is a side elevation of one end of a car truck showing the journal-box equipped with wear-plates constructed in accordance with this invention;

Fig. 2 is a plan view on an enlarged scale 80 of the journal-box, partly in section, showing the wear-plates in position in their respective sliding guideways;

Fig. 3 is a front elevation, partly in section, on an enlarged scale, of the journal-box and showing the wear-plates and the means utilized for holding the said wear-plates in position; and

Fig. 4 is a view in perspective of one of the wear-plates.

90 As illustrated in the drawings of Fig. 1, the truck consists of the usual frame comprising the horizontal supporting bar 4 from which is suspended the stirrup 5 serving as a support for the spiral spring 6 and 95 the leaf-spring 7, which serve to resiliently support the car-body. The brake 8 is likewise suspended from the frame in any suitable manner. The frame carries at its forward end a yoke 9 which is fitted with two vertical pedestals 10 and 11, over which the pedestal ways 12 and 13 on each side of the journal-box 14 are fitted. The journal-box 14 is positively positioned vertically between the two pedestals 11 and 12 by the 100 axle 15 which rides in a suitable bearing 16 situated in the journal-box 14.

105 Between the upper face 17 of the journal-box and an arm 18 interconnecting the pedestals 10 and 11 is a spiral spring or springs 110 such as 19 which helps to support the weight of the car and which is partly compressed

when the car-body is placed in position on the truck. The pedestal ways 12 and 13 in the journal-box are protected from wear and chafing by the wear-plates or jibs 20, illustrated in perspective in Fig. 4. These wear-plates are suitably hardened to withstand the continual friction resulting from the vertical reciprocations of the journal-box on the pedestals 10 and 11 caused by the absorption of jolts and jars by the spiral spring 19.

As illustrated in Fig. 4, the preferred form of wear-plate comprises an upper arcuated surface 21, the curvature of which is such as to substantially conform to the curvature of the inner surface of the spiral spring 19. This upper portion of the plate may assume any desired form, depending upon the journal-box and type of truck it is to be used with. This arcuated surface 21 is interconnected by a substantially right angularly-disposed portion 22 with the flat vertical wearing surface 23. Obviously this wearing surface may assume a large variety of forms curved and otherwise, depending upon the form and shape of the pedestals. The wearing surface 23 carries two substantially right-angularly disposed shoulder-plates 24 and 25 which fit over the lateral sides of the forwardly-disposed ends of the pedestals 10 and 11; the wearing or friction-plates 23 fitting over the vertical surfaces 26 of the pedestals. Obviously the wear or gib plate could be used without the shoulder plates 24 and 25. The lower end of the wear-plate 23 is turned up at an angle to form a hook-like member 27 which fits over a lug 26 attached to the lower face of the journal-box.

40 The method of placing these wear or gib plates in position on the journal-box will now be briefly described: As will be apparent from the foregoing description, the plates are formed to fit the pedestal way of the journal-box; the lower end 27 thereof being hooked over the lug on the lower face of the box, while the upper angularly-disposed portion 22 thereof is formed to fit over the top of the box. The upwardly-disposed arcuated portion 21 terminates in the first coil of the spring 19. It will therefore be obvious that, when the journal-box is relieved of the weight of the superposed structure consisting principally of the car body and truck, the journal-box can be readily slid out from the pedestals 10 and 11, after which the wear-plates can be easily hooked in position in each of the pedestal ways 12 and 13. The journal-box is then placed back into position between the pedestals 10 and 11 and the lower coil of the spring 19 hooked over the arcuated surface 21 of the wear-plate 20. It will be evident that any other means can be utilized instead of the lower coil of the spring 19 to

hold the arcuated surfaces 21 of the wear-plates together, and thereby cause the wear-plates to fit snugly and tightly against the journal-box. When the journal-box is thus positioned the wear-plate will be positively and rigidly held in position, due to the hook connection at the bottom of the journal-box and the overlapping of the spiral spring 19 on the extreme upper arcuated surface 21 of the wear-plate. When the wear-plates are thus placed in position and subsequently the weight of the car-body is placed on the truck, the journal-box spring 19 will be partially compressed and thus further secure the wear-plates in position and very firmly and rigidly hold them to prevent rattle and wear.

It will be evident from the foregoing description that wear-plates constructed in accordance with this invention may be very readily removed and renewed without the use of tools, since no rivets are utilized and no permanent connection such as results from rivets or welding or any similar fastening means now common to the art of truck-building is utilized. The various expedients now practised in the art of truck-building for holding the wear-plates permanently in position, such as riveting and welding, etc., are replaced, in wear-plates constructed in accordance with this invention, by the force exerted by the weight of the car through the spiral spring 19, which force is exerted to firmly secure and hold the wear, gib or chafing, plates in position and prevent rattle. In other words, wear-plates constructed in accordance with this invention are designed so that when the lower end of the wear-plate is hooked over the lower edge of the journal-box, the wear-plate will snugly fit in the pedestal ways and the upper arcuated end of the wear-plate will be positioned and project so as to snugly fit under the lower coil of the journal-box spring or springs, said spring or springs, due to the weight of the car serving to firmly hold the plate in position.

Obviously, this invention is not limited to the preferred form thereof herein illustrated and described, but is capable of many variations within the spirit and scope of the invention as set forth in the following claims.

I claim as new and desire to secure by Letters Patent of the United States:

1. The combination with a journal-box of a wear-plate therefor comprising means non-permanently fixed for securing it to said box and means operating on said first mentioned means whereby the weight of the superposed structure is used to firmly secure the plate to said box to prevent rattling of the said plate.

2. The combination with a journal-box of a wear-plate therefor comprising means for

securing it to said box in a readily detachable manner and means operating on said first mentioned means whereby the weight of the superposed structure is used to firmly

5 secure the plate to said box to prevent rattling of the said plate.

3. A wear-plate for journal-boxes comprising in combination, a wearing-plate and means depending from either end of said 10 plate for securing said plate to the journal-box in a non-permanent manner and means operating on said first mentioned means at one end of said plate whereby the weight of the superposed structure is used to firmly 15 secure the plate to said box to prevent rattling of the said plate.

4. In a wear-plate for journal-boxes, in combination, a wearing plate, guiding surfaces supported by the lateral edges of said 20 wearing plate, an arcuated supporting means for said wearing-plate depending from one end thereof, and a hook securing means depending from the other end of said wearing plate.

25 5. In a wear-plate for journal-boxes, in combination, a wear-plate comprising a flat surface, guide-plates disposed in substantially right-angular positions on the lateral edges of said flat-plate, a hooking means depending from the lower end of said flat plate, and an arcuated supporting plate depending from the upper end of said flat plate.

6. The combination with a journal-box 35 and journal-box spring of a wear-plate comprising means at either end for securing it to said box, said means operating to loosely suspend said wear-plate on said box and op-

erating to securely fit said plate on said box by the weight exerted through the journal- 40 box spring due to the weight of the car body.

7. The combination with a journal-box and journal-box spring of a wear-plate comprising a hook means for hooking over the end 45 of the journal-box at one end thereof, and an arcuated means for hooking under the journal-box spring at the other end thereof, said hook and arcuated means serving together with said spring to firmly secure said wear- 50 plate to said box.

8. The combination with a journal-box and journal-box spring of a wear-plate comprising a wearing surface and laterally substantially 55 right-angularly disposed shoulders which snugly fit over journal-box pedestals, a hook for securing the lower end of said plate to the lower end of said box, and means for securing the upper end of said plate to said box under the journal-box 60 spring, whereby said plate is firmly and securely fastened to said journal-box in a non-permanent manner.

9. The combination with a journal-box and journal-box spring of a wear-plate comprising means at one end thereof for securing it to said box, said means operating to loosely suspend said wear-plate on said box and operating to securely fix said plate on said box by the weight exerted through the 70 journal-box spring by the weight of the superpose structure.

In witness whereof, I have hereunto subscribed my name.

EDWARD W. ANGER
